UNITED STATES PATENT OFFICE.

JAMES SANDFORD GANDER, OF STRATFORD, LONDON, ENGLAND.

APPARATUS FOR SEPARATING FLUIDS OF DIFFERENT SPECIFIC GRAVITIES.

1,266,008.

Specification of Letters Patent. Patented May 14, 1918.

Application filed January 13, 1916. Serial No. 71,904.

To all whom it may concern:

Be it known that I, JAMES SANDFORD GANDER, a subject of the King of Great Britain and Ireland, residing at 76 Romford Road, Stratford, London, England, have invented certain useful Improvements in Apparatus for Separating Fluids of Different Specific Gravities, of which the following is a specification.

10 This invention relates to automatic ejectors or ejectors operating somewhat in the manner of a steam trap, that is to say the apparatus depends for its action upon the difference in specific gravity between the liquids or gases to be ejected and the liquids or gases and the like to be retained. This difference is utilized in the form of mechanical effort multiplied by suitable mechanism so that the apparatus is capable of 20 working at high or low pressure.

The invention has for its object to provide an improved apparatus of this kind which will operate for,—

- (a) Draining water or other liquids from 25 oils or other liquids, gases and the like.
- (b) Draining gases and the like from oils and other liquids.
- (c) Performing both duties together.

The improved apparatus consists of a 30 float mounted on a shaft or pivot in a closed chamber, a lever preferably counterweighted and pivoted on the chamber and adapted to be operated by a cam or like member from the shaft on which the float is pivoted, and 35 means whereby the pivoted lever is coupled to and adapted to operate a valve or valves through which the liquid or gases are ejected.

Referring to the drawings,—

40 Figure 1 is a sectional end elevation of one form of apparatus made in accordance with this invention.

Fig. 2 is a sectional plan.

Fig. 3 is a longitudinal section.

45 Fig. 4 is a section of the cover of a modified construction showing part of the mechanism mounted thereon.

Fig. 5 is an elevation of the cover shown in Fig. 4.

50 In one construction of apparatus made in accordance with this invention a container *a* is provided in which is mounted a float *b* of cylindrical form with dished ends, the said float being adjusted so that it sinks in the lighter medium and rises in the heavier. The float is weighted as required by means

of a screwed plug *c* on the shell of the float, which allows for the admission of weighting material to the inside of the float. An adjacent eyebolt *d* allows for the suspension 60 of the float during this preliminary operation. For all ordinary purposes the adjustment may be permanently made during the process of manufacture.

The float is mounted on a shaft *e* adapted to rock in bearings *f f* secured to the container shell, the said shaft being attached to the float in the direction of its length on its circumference. The float moves through part of a circle of which the bearing shaft forms the center. At one end of the shaft, and between the end of the float and the adjacent bearing, an eccentric disk *g* or cam with a small throw is fitted. The lifting of the float causes the eccentric disk 75 or cam to lift or operate the end of a forked lever *h* mounted alongside the end of the float and this motion is transmitted by suitable mechanism to a spindle *j* which carries at its lower end a coned valve *k* seated on 80 an outlet *m*, which valve allows the heavier medium at the bottom of the apparatus to be ejected by its own weight or by the pressure inside the container. The forked lever *h* is supported by bearings *n n* attached to 85 the shell of the container on the side opposite the shaft bearing or in other suitable position. A counterweight *o* is provided on the lever to neutralize or minimize the weight thereof and of the valve spindle as 90 desired.

The valve spindle is connected to the forked lever by links *p* which are fitted to pins *q* on the lever *h* and to a suitable sliding knuckle *r* on the valve spindle. The 95 sliding knuckle is an easy fit on the valve spindle. A light spring *s* disposed immediately below the knuckle is adapted to be compressed by a circular nut *t* against a tapered washer *v* in such a manner that the 100 knuckle is not compressed between the tapered washer and the flange on the spindle. This arrangement allows the spindle to be revolved by hand for grinding purposes, without removing any of the adjacent parts 105 except a nut *w* which is provided at the top of the spindle. The spring prevents any damage which might occur to the mechanism by reason of careless adjustment or an obstruction getting under the valve face. 110 In the event of any such accident causing the valve to jam while the float is still exert-

ing force in a downward direction, the sliding knuckle *r* presses down the tapered washer and compresses the spring.

The valve seat plug 2 is designed for easy removal and changing. This and another plug 3 at the top of the spindle in the casting also act as guides for the movement of the spindle in a vertical direction. On setting up the apparatus the valve seat plug 10 2 is screwed into its boss until the valve face bears against the valve point *h* on the spindle when the float is at the bottom of its travel. The valve seat plug 2 is then secured by a lock nut 4.

15 A chamber 5 is provided at the top of the container and is fitted with a removable filtering disk 6 to arrest any foreign matter which might affect the closing of the valve. A further filter 7 is attached to the valve 20 seat plug as an additional precaution. This filter may be in the form of a cage and the upper part also adapted to act as a guide to the valve spindle. At the sides of the said 25 upper chamber are openings 8 and 9 for the admission and exit of the medium to be dealt with.

In order that the float may be agitated if desired a spindle 10 is provided and for the purpose of lifting the valve off its seat a 30 spindle 11 is provided in each case passing out through a suitable stuffing box in the wall of the casing. In the former case the inner end of said spindle bears against the bottom of the float *b*; in the latter case the 35 inner end of said spindle bears upon one end of a pivoted lever 12 the other end of which bears upon a collar 13 on the valve spindle *j* so as to raise same as required.

A cock at the end of the hollow plug 14 40 provided at the top of the chamber allows for the expulsion of air when starting, or for supply connection to the gas extracting part of the apparatus when this is fitted.

In operation the liquids to be separated 45 are passed into the chamber 5 by the inlet 8 above the filter 6. The filtering medium is mounted upon a removable division plate which is provided with an internal pipe 15 and is held down by the hollow plug through 50 which gases may be passed from the lower half of the chamber 5. All that passes through the filter is taken to the middle of the container by the pipe 15. The liquids separate in the container *a*, the heavy material passing out through the valve 2 and the light material rising into the lower part of the container chamber 5 is discharged 55 through one or more of the outlets 9 9.

A particular feature of the invention is 60 the construction of the float and of the mechanism operated by the float which renders it possible to eject heavier or lighter mediums against pressure automatically.

The above description is of a construction 65 of apparatus for and the apparatus serves

for drawing water or other liquids from oils or other liquids, gases and the like, where the valve is at the bottom.

In the construction shown in Figs. 4 and 5, the cam shaft is formed in two parts, one 70 part is mounted on the container and one part on the cover of the container. The valve, filter, balanced lever, and link connection are also mounted on the cover.

The end of the float shaft *e* by the chamber cover 16 is adapted to engage with the end of a shaft 17 which is mounted on bearings 18, 18 attached to the said cover and which carries an eccentric cam or disk *g*. The lifting of the float causes the cam or 80 disk to operate the end of a forked lever *h* which is mounted on suitable bearings *n* attached to the cover 16. This motion is transmitted by suitable mechanism to a spindle *j* which carries a valve at its lower end seated 85 on an outlet, which valve allows the heavier medium at the bottom of the apparatus to be ejected by its own weight or the pressure in the chamber. A counterweight *o* is provided on the lever to neutralize or minimize 90 the weight of the various parts as desired.

The valve spindle *j* is connected to the forked lever *h* by links not shown which are fitted to pins on the lever end and to a suitable sliding knuckle *r* on the spindle. The 95 spindle sliding knuckle is an easy fit on the valve spindle. A light spring *s* disposed immediately below the knuckle is adapted to be compressed by a circular nut *t* against a tapered washer *v* in such a manner that the knuckle 100 is not compressed between the tapered washer and the flange on the valve spindle. This arrangement allows the spindle *e* to be revolved by hand for grinding purposes without removing adjacent parts. The 105 spring prevents any damage which might occur to the mechanism by reason of careless adjustment or obstruction of valve face. In the event of any such accident causing the valve to jam while the float is exerting force 110 in a downward direction, the sliding knuckle presses down the tapered washer and compresses the spring.

The cam shaft 17 which transmits the mechanical effort of the float chamber *e* passes 115 through a stuffing box 19 in the container cover 16 and engages at one end with the extremity of the float shaft which is suitably recessed to receive the shaped end. The removal of the collar nut 20 on the cam shaft 120 permits of its withdrawal for disconnection or the removal of the cover. A flexible coupling 21 connects the spindle with the discharge valve to allow for incorrect lining up. The discharge valve should be preferably of a type which permits of grinding in by the operation of rotating its spindle by means of the square on the top but any type of valve may be fitted. The pressure on 125 valve area due to the pressure inside the 130

chamber may be utilized to assist or retard the opening or closing of the valve according to the side of the valves used for exit. Suitable guides are fitted to the valve 5 spindle. The forked lever y which is supported on bearings attached to the topmost valve spindle guide causes the valve spindle to lift, if desired (when turned by means of the squared end) by lifting the collar immediately above.

In order that the valve may not be obstructed by portions of solid matter a portable strainer 22 is fitted. By removing the filter cover 23 and unscrewing the nut 24 holding up the strainer it may be removed for inspection or cleaning. To allow this 15 operation the inlet valve is shut to cut off the supply from the interior of the chamber.

The medium which it is desired to separate 20 passes from the container through the inlet valve 25 to the passage 26 between the filter casings, from thence to the interior of and through the strainer, leaving the inner strainer chamber by an internal pipe 25 which connects through the container cover with the discharge valve 28. In cases where filtration is accomplished previously or is not required the internal pipe may be removed and the discharge valve allowed to 30 operate directly from the material in the chamber. To adapt the machine to the conditions of pressure or quantities with which it is desired to deal the throw of the cam or the area of the valve discharge may be 35 varied.

For the purpose of filtering liquids to be dealt with in the chamber the upper part of the chamber may be fitted with a separate compartment as described with reference 40 to Figs. 1 to 3 containing a removable filtering cage or disk in such manner that no portion of solid matter can pass which might tend to obstruct the working of the mechanism, the inlets and outlets being disposed at opposite sides of the filter.

The particular feature of this construction of apparatus is that all parts of the mechanism, except the float and the float shaft, are visible and accessible for adjustment 50 while the machine is in operation. The container cover need not be removed except for examination of the interior of the chamber. This type of construction is suitable for dealing with large quantities 55 of liquids, according to the scale of build, at low and intermediate pressures, but may also be used if required for high pressures.

What I claim and desire to secure by Letters Patent is:—

60 1. Apparatus for separating fluids of different specific gravities comprising a closed container, an inlet for admitting the fluids to the chamber, an outlet for discharging the fluids from said container, a closed 65 water tight float pivoted in said container,

said float being adapted to rise in one of the fluids and to sink in the other fluid, a valve adapted to open and close one of said outlets, and means for converting the radial movement of the float to a motion to move 70 the valve, and means whereby the amount of lift of the valve may be altered, while the machine is in active operation.

2. Apparatus for separating fluids of different specific gravities comprising a closed 75 container, an inlet for admitting the fluids to the chamber, an outlet for discharging the fluids from said container, a closed water tight float pivoted in said container, said float being adapted to rise in one of the fluids and to sink in the other fluid, a valve adapted to open and close one of said outlets, and means for converting the radial movement of the float to a motion to move 80 the valve, and means whereby the valve face may be revolved upon its seat without disconnecting any part of the movable mechanism and without removing the fluids from the container in which the float operates.

3. Apparatus for separating fluids of different specific gravities comprising a closed 85 container, an inlet for admitting the fluids to the chamber, an outlet for discharging the fluids from said container, a closed water tight float pivoted in said container, 90 said float being adapted to rise in one of the fluids and to sink in the other fluid, a valve adapted to open and close one of said outlets and means for converting the radial movement of the float to a motion to move 95 the valve, and means whereby the amount of lift of the valve may be altered, and means whereby the valve face may be revolved upon its seat without disconnecting any part of the movable mechanism and 100 without removing the fluids from the container in which the float operates, said apparatus being capable of discharging fluids automatically when the said fluids are at 105 high or low pressure.

4. Apparatus for separating fluids of different specific gravities comprising a closed 110 container, an inlet for admitting the fluids to the chamber, an outlet for discharging the fluids from said container, a closed water tight float pivoted in said container, 115 said float being adapted to rise in one of the fluids and to sink in the other fluid, a valve adapted to open and close one of said outlets, and means for transmitting the angular motion of the float to the valve comprising a shaft on which the float is mounted, a cam on said shaft, a balanced lever adapted to engage said cam and a link connection between the said lever and the 120 valve.

5. Apparatus for separating fluids of different specific gravities comprising a closed 125 container, an inlet for admitting the fluids to the chamber, an outlet for discharging 130

the fluids from said container, a closed water tight float pivoted in said container, said float being adapted to rise in one of the fluids and to sink in the other fluid, a 5 valve adapted to open and close one of said outlets, and means for transmitting the angular motion of the float to the valve comprising a shaft on which the float is mounted, a cam on said shaft, a balanced lever 10 adapted to engage said cam and a link connection between the said lever and the valve, a buffer spring being disposed between the said valve and the said lever and means for permitting the valve spindle to be moved 15 axially.

6. Apparatus for separating fluids of different specific gravities comprising a closed container, an inlet for admitting the fluids to the chamber, an outlet for discharging 20 the fluids from said container, a closed water tight float pivoted in said container, said float being adapted to rise in one of the fluids and to sink in the other fluid, a valve adapted to open and close one of said outlets, and means for transmitting the angular motion of the float to the valve comprising a shaft on which the float is mounted, a cam on said shaft, a balanced lever adapted to engage said cam and a link connection 25 between the said lever and the valve, a buffer spring being disposed between the said valve and the said lever and means for permitting the valve spindle to be moved axially, said spindle being free to revolve 30 on its axis.

7. Apparatus for separating fluids of different specific gravities comprising a closed container, an inlet for admitting the fluids to the chamber, an outlet for discharging 40 the fluids from said container, a closed water tight float pivoted in said container, said float being adapted to rise in one of the fluids and to sink in the other fluid, a valve adapted to open and close one of said outlets, and means for transmitting the angular motion of the float to the valve comprising a shaft on which the float is mounted, a cam on said shaft, a balanced lever adapted to engage said cam and a link connection 45 between the said lever and the valve, a buffer spring being disposed between the said valve and the said lever and means for permitting the valve spindle to be moved axially, said spindle being free to revolve 50 on its axis.

its axis, and means for lifting the valve 55 from the valve face, adapted to be operated from outside the container.

8. Apparatus for separating fluids of different specific gravities comprising a closed container, an inlet for admitting the fluids 60 to the chamber, an outlet for discharging the fluids from said container, a closed water tight float pivoted in said container, said float being adapted to rise in one of the fluids and to sink in the other fluid, a valve 65 adapted to open and close one of said outlets, and means for transmitting the angular motion of the float to the valve comprising a shaft on which the float is mounted, a cam on said shaft, a balanced lever adapted 70 to engage said cam and a link connection between the said lever and the valve, a buffer spring being disposed between the said valve and the said lever and means for permitting the valve spindle to be moved 75 axially, said spindle being free to revolve on its axis, and means for lifting the valve from the valve face, adapted to be operated from outside the container, and means for agitating the float adapted to be operated 80 from outside the container, said means for lifting the valve being adapted to be operated independently of the means for agitating the float.

9. In apparatus for separating fluids of 85 different specific gravity, a float adapted to rise in one of the fluids and to sink in the other fluid and a valve adapted to be opened by the motion of the float to discharge one 90 of the fluids, the means for transmitting the motion of the float to the valve comprising a shaft on which the float is mounted, a cam on said shaft, a balanced lever adapted to engage said cam and a link connection between the said lever and the valve, said cam 95 shaft being formed in two parts detachably connected together, one part being mounted on the container and one part on the cover of the container, said valve, balanced lever and link connections being also mounted on 100 the cover of the container.

In witness whereof, I have hereunto signed my name in the presence of two subscribing witnesses.
